ABSTRACT

Successive samples are taken periodically from a body of liquid with the aid of pressurized fluid serving as both timing medium and sample propellant. The sampling apparatus is adjustable as to interval between successive samples, duration of taking of each sample, and sample lift.

1
LIQUID SAMPLING

This invention relates to sampling a liquid medium such as preliminary to determination of the composition thereof or of contaminants therein, concerning especially such sampling accomplished by use of a pressurized fluid for sample propulsion.

Manual techniques for sampling a medium for analysis or related purposes are giving way to automatic sampling, often electrically operated. Devices for setting frequency of sampling include spring-driven and electrical timing devices. Electrical operation is hazardous in an explosive atmosphere, such as may be encountered in oil refineries and other industrial operations, in sewers and sewage treatment plants, and in pollution-ridden areas. Electrical power lines are not available at remote sampling sites, and batteries often are cumbersome or otherwise unsatisfactory and require frequent replacement. Spring-winding is inconvenient, and spring motors are a source of maintenance requirements.

A primary object of the present invention is provision of a continuous-range adjustable high-to-low lift system for fluid-energized sampling of liquids.

Another object is flow-regulated control of sampling frequency and duration in such a system.

A further object is accomplishment of the foregoing objects by means of relatively simple apparatus.

Other objects of this invention, together with means and methods for attaining the various objects, will be apparent from the following description and the accompanying schematic drawing of a preferred embodiment thereof, which is presented by way of example rather than limitation.

In general, the objects of the present invention are accomplished with the aid of pressurized fluid serving as both timing medium and sample propellant. The apparatus of this invention is adjustable as to interval between successive samples and the duration of taking of each sample, by control of flow rates of the pressurized fluid, and is adjustable in sample lift by regulation of fluid pressure.

The single FIGURE of the drawing is a schematic representation of the invention.

Source 10 of pressurized fluid connects via line 11, which conveniently contains on-off valve V₁, to two parallel branch lines, which may be viewed as low-pressure and high-pressure conduits, respectively.

First or low-pressure conduit 13 contains, in sequence, pressure regulator R₁, first flow-regulating valve V₂, pressure-responsive switching valve S₁, and finally second flow-regulating valve V₃, whose outlet 16 vents to the atmosphere. Accumulator tank A and low-pressure gauge P₁ are interconnected to the first conduit between the first flow-regulating valve and the pressure-responsive switching valve. The latter valve normally closes the conduit at its location but vents the downstream portion thereof via vent 12 thereof; it is responsive to the fluid pressure in the immediately upstream portion of the conduit, which interconnects directly to the accumulator tank and the pressure gauge, and opens at a predetermined pressure (simultaneously closing the vent) and recloses at a lower predetermined pressure.

Second or high-pressure conduit 15 contains adjustable pressure regulator R₂, which is normally set for a higher pressure than that for which low-pressure regu-

lator R₁ in the first conduit is set. Pressure gauge P₂ is connected to the regulated downstream portion of this second conduit, which terminates in normally closed second pressure-responsive switching valve S₂ connected to sense and be responsive to (i.e., opened at a given level of) the pressure immediately upstream from valve V₃ in first conduit 13.

As shown connected for use, the outlet of switching valve S₂ is connected via line 21 to sample intake chamber 22 submerged in the body of liquid to be sampled. From the sample intake chamber, sample line 23 (with dip tube portion shown in broken lines inside the chamber) leads to sample collection container 24, which has vent tube 25 to the atmosphere.

Operation of the apparatus of this invention is readily understood by reference to the foregoing description and the accompanying illustration thereof.

With on-off valve V₁ in the on position, fluid under pressure from source 10 flows through line 11 into branch line 13, being the first or low-pressure conduit. Reduced to a predetermined pressure by pressure regulator R₁, the fluid flows on through the line at a rate determined by the setting of first flow-regulating valve V₂ and the pressure downstream therefrom, as indicated on low-pressure gauge P₁. The fluid collects at gradually increasing pressure, principally in accumulator tank A, until the switching pressure of normally closed first pressure-responsive switching valve S₁ is reached, whereupon the valve switches to the open position and releases the accumulated fluid to flow downstream and through second flow-regulating valve V₃ to the atmosphere at a rate controlled by the setting thereof. The surge of fluid into the part of branch conduit 13 located between the first switching valve and the second flow-regulating valve is sensed by sensing line 14 to normally closed second pressure-responsive switching valve S₂, which itself is located in second or high-pressure branch conduit 15. The resultant opening of the latter switching valve permits fluid to flow at such pressure, established by adjustable second pressure regulator R₂ and indicated on second pressure gauge P₂, into line 21 to sample intake chamber 22 submerged in the body of liquid to be sampled.

The sample chamber has a check valve (not shown) that enables liquid to enter the chamber, but when fluid under pressure is received via line 21 the check valve is forced shut and the liquid inside is propelled via line 23 therefrom into collection vessel or sample container 24, and propellant fluid is vented through vent 25 of the sample container. The flow of fluid at this relatively high pressure—as compared with the pressure in the other branch line—continues until second flow-regulating valve V₃ at the end of the low-pressure conduit has dropped the pressure therein sufficiently for first switching valve S₁ to reclose. Reduction of pressure in the accumulator tank to the reclosing level for first switching valve S₁ cuts off the supply of fluid into the terminal portion of the first conduit, and reclosing of S₁ also vents that terminal portion to the atmosphere through vent 12, thereby hastening the loss of pressure therein. Switching valve S₂—usually set to close below the reclosing pressure of S₁—then recloses, whereupon the system recycles. Thus, first flow-regulating valve V₂ mainly determines the interval between successive samples and second flow-regulating valve V₃ determines the duration of the time over which each sample

is taken, which usually is much shorter than the period between successive samples.

The source of fluid under superatmospheric pressure may be located internal or external to the apparatus. The fluid source may comprise a reservoir of suitable fluid, such as nitrogen, helium, or other gaseous medium that is inert relative to the body of liquid and preferably also to any chemical tests to be performed upon the samples propelled thereby from the body of liquid. If air is not objectionable as a propellant, the source may be a tank of compressed air or a line from an air compressor wherever located.

Conventional materials of construction inert to the liquid being sampled are suitable for the various valves and other components. The flow-regulating valves, in addition to controlling the flow of fluid therethrough, may comprise visual indicators of flow rate, as by means of one or more balls or similar floats in a tapered tube as illustrated (e.g., FIG. 2) and described in U.S. Pat. No. 2,720,109. The pressure-responsive switching valves may be of the W-spring type shown (e.g., FIG. 5) and described in that patent or may be of the ball-controlled type shown (e.g., FIGS. 2a, 2b, 3a, 3b) and described in U.S. Pat. No. 3,751,983. The sample chamber conveniently is constructed as shown (FIGS. 6 and 5, respectively) and described in each of those patents.

By adjusting the setting of the pressure regulator for the high-pressure conduit the operator of this apparatus can adapt it readily to different lift requirements. Thus, for a 100-ft. deep well the source pressure (of perhaps 250 psi) may be dropped to about 50 psi. The pressure in the low-pressure line is conveniently reduced to about one atmosphere and the low-pressure switching valve set to open at about 16 psi and to reclose at about 14 psi, for example. The high-pressure switching valve may open at not so high a pressure (e.g., 15 psi) and reclose at a somewhat lower pressure (e.g., 5 or 10 psi). Alternatively, the respective switching valves could be set so that the band through which the low-pressure valve operates is broader than that through the high-pressure valve operates (e.g., first valve to open at 25 psi and reclose at 10 psi, high-pressure valve to open at 20 psi and reclose at 15 psi) but this is not preferred because of the excessive venting of fluid by the timing circuitry and perhaps unduly short resulting sample duration.

Although only a single embodiment of this invention has been described and illustrated here, modifications may be made therein, as by adding, combining, or subdividing parts or steps, or by substituting equivalents, while retaining distinctive advantages and benefits of the present invention, which itself is defined in the following claims.

The invention claimed is:

1. In liquid sampling apparatus operable from a source of propellant fluid under pressure, to collect samples of liquid from a body thereof, the improvement comprising a first conduit having means therein operable at relatively low pressure for controlling the interval of time between successive samples and the duration of time for collecting each sample and a second conduit having means therein normally closing off the body of liquid from the pressurized fluid and adapted to open to admit such fluid under relatively high pressure to propel a sample therefrom, the respective conduits being connected in parallel to the source of pres-

surized fluid; the first or timing means comprising in the first conduit a sampling interval flow-regulating valve and, in sequence downstream therefrom, an accumulator tank, a first pressure-responsive switching valve, and a sample duration flow-regulating valve, to the atmosphere; the first switching valve being interconnected to sense the pressure of fluid accumulated immediately upstream therefrom, being normally closed below a given accumulated pressure, and adapted to open at a given higher accumulated pressure; the second or sample propulsion means comprising a second pressure-responsive switching valve in the second conduit, being normally closed to the body of liquid to be sampled and interconnected to sense the accumulated low pressure while the first pressure-responsive switching valve is open, and being adapted to open at a given pressure therein and to reclose at a given lower pressure therein.

2. Liquid-sampling apparatus according to claim 1, including an adjustable pressure regulator in the second conduit upstream from the switching valve therein.

3. Liquid-sampling apparatus according to claim 1, including a pressure regulator in the first conduit upstream from the other components therein.

4. In liquid-sampling apparatus operable from a source of propellant fluid under pressure, to collect samples of liquid from a body thereof, the improvement comprising a first or low-pressure conduit and a second or high-pressure conduit for connection in parallel to the source of pressurized fluid; in the first conduit, a low-pressure regulator followed by a flow-regulating valve and, in sequence downstream therefrom, an accumulator tank, a first pressure-responsive switching valve, and a second flow-regulating valve, to the atmosphere; the switching valve being interconnected to sense the pressure of fluid accumulated immediately upstream therefrom, being normally closed below a given accumulated pressure, and being adapted to open at a given higher accumulated pressure; in the second conduit an adjustable pressure regulator and a second pressure-responsive switching valve, the latter being normally closed to the body of liquid to be sampled and interconnected to sense the pressure in the first conduit between the first switching valve and the second flow-regulating valve, and being adapted to open at a given pressure therein and to reclose at a given lower pressure therein.

5. Liquid-sampling apparatus according to claim 4, wherein the second switching valve is adapted to open at a pressure below the pressure at which the first switching valve is adapted to open.

6. Liquid-sampling apparatus according to claim 5, wherein the second switching valve is adapted to close at a pressure below the pressure at which the first switching valve is adapted to close.

7. In liquid-sampling apparatus operable from a source of propellant fluid under pressure, to collect successive samples of liquid from a sample intake means immersed in a body thereof, the improvement comprising a first conduit and a second conduit for connection in parallel to the source of pressurized fluid; a first, relatively low-pressure regulator in the first conduit, and a second, relatively high-pressure regulator in the second conduit, at least the second pressure regulator being adjustable in regulated pressure; in the first conduit a first adjustable flow-regulating valve for controlling the interval between successive samples

and, in sequence downstream therefrom, an accumulator tank, a first pressure-responsive switching valve, and a second adjustable flow-regulating valve, for controlling the duration of collecting each sample, and leading to the atmosphere; the switching valve being interconnected to sense the pressure of fluid accumulated immediately upstream therefrom, being normally closed below a given accumulated pressure and venting the conduit downstream therefrom, and being adapted to open and cease venting at a given higher accumulated pressure; and a second pressure-responsive switching valve downstream from the pressure regula-

tor in the second conduit, being normally closed to the body of liquid to be sampled and interconnected to sense the pressure accumulated in the first conduit so long as the first pressure-responsive switching valve is open, and being adapted to open at a given sensed pressure below the higher given accumulated pressure to pass fluid at relatively high pressure to the sample intake means for propelling the sample therefrom and to reclose at a given pressure lower than the first given accumulated pressure, at which the first switching valve recloses.
